UNITED STATES PATENT OFFICE.

PERCIVAL J. OLDERSHAW, OF HARRINGTON, WASHINGTON.

PRESS FOR SEPARATING SHAFTS FROM GEARS AND THE LIKE.

Application filed December 19, 1921. Serial No. 523,481.

To all whom it may concern:

Be it known that I, PERCIVAL J. OLDERSHAW, a citizen of the United States, residing at Harrington, in the county of Lincoln 5 and State of Washington, have invented new and useful Improvements in Presses for Separating Shafts from Gears and the like, of which the following is a specification.

The object of my said invention is the provision of a simple and durable press for separating shafts from gears and other elements mounted thereon, and one possessed of a wide range of utility.

To the attainment of the foregoing, the invention consists in the improvement as hereinafter described and definitely claimed.

In the accompanying drawings, forming part of this specification:—

Figure 1 is a view partly in side elevation 20 and partly in vertical section, showing my novel press.

Figure 2 is a front elevation of the same with parts in section.

Figure 3 is a top plan view of the press.

Figure 4 is a section taken in the plane indicated by the line 4—4 of Figure 2, looking downwardly.

Figure 5 is a perspective of a special base plate for use in the press frame.

Figure 6 is a perspective of another base plate for use in the frame, it being understood that there are preferably eight of the said plates provided for use interchangeably in the press frame, the openings in the plates 35 varying in size to receive shafts of different diameters.

Figure 7 is an enlarged perspective of a member designed for interposition between the screw of the press and the shaft to be separated from a gear or other element thereon, it being understood that six of the said members of different sizes and lengths are provided for use interchangeably in the press.

Similar numerals of reference designate corresponding parts in all of the views of the drawings.

In Figures 1, 2 and 3 I show a portion of a bench top 1, and on the said bench top 1 is fixed by screws 2 or other appropriate means a bracket 3 the forward portion 4 of which is comparatively thick for the connection by screws 5 or other appropriate means of the ends of a pendent U-shaped frame 6 55 comprised in my improvement. In addition to the arms having the said end portions, the

frame 6 is provided with a lower cross portion 7 in which is a bifurcation 8 of a size sufficient to receive the largest shaft on which my novel press is adapted to operate. 60

As best shown in Figure 2, the forward portion 4 of the bracket 3 is provided with a central threaded aperture 9 to receive the threaded shank of the press screw 10, which screw is provided at its upper end with an 65 appropriate handle 11. In the lower end of the screw is a shallow socket 12.

My invention contemplates the use on the lower portion 7 of the press frame 6 of a plurality of base plates 13, interchangeably, 70 the said plates 13 having kerfs 14 of different sizes. I would also have it understood that for special work I may employ a plate 13^a, Figure 5, this plate being peculiar in that its kerf 14^a is defined by a flange 15 of 75 less thickness than the remainder of the plate, a rabbet 16 being afforded between the upper side of the frame 15 and the upper side of the plate 13^a. Said plate is hardened on account of its being extra thin. 80

My invention also contemplates the employment of an anti-friction member 17 between the lower end of the screw shank and the upper end of a shaft such as 18 which is to be separated from a gear or other element 85 19 thereof. I prefer to provide the members 17 in three different lengths, and two different sizes for use interchangeably. I also prefer to provide the members 17 in three different sizes for use interchangeably according to the location of the gear 19 on the shaft 18, and it will be noted that each of the members 17 is provided at its lower and upper ends with tapered protuberances 20, one of the said protuberances to take into 95 the socket 12 of the screw, and the other protuberance to take into the socket generally provided in the end of the shaft represented by 18.

In the practical use of my novel press, an 100 appropriate base plate is arranged on the bottom of the frame 6, and a shaft, as 18, is arranged in the bifurcation of the base plate and so that the gear 19 carried by the shaft is superimposed on the base plate. An anti-friction member is then engaged with and held on the upper end of the shaft, after which the screw shank is fed downwardly and engaged with the protuberance at the upper end of the member 17. The screw is 105 then turned downwardly to force the shaft 18 downwardly through the gear 19 with 110

the result that the gear will be rendered loose on the shaft and can be readily disassociated therefrom.

- It will be apparent that because of the 5 interposition of the member 17 between the shaft 18 and the screw, a powerful thrust can be exerted on the shaft and yet the screw will be subject to but little torsional friction. From this it follows that the screw can 10 be turned with but little effort on the part of the operator. All wearing parts of the improvement are case-hardened and the press can be made from any material suitable to its use.
- 15 I have entered into a detailed description of the construction and relative arrangement of the parts embraced in the present and preferred embodiment of my invention in order to impart a full, clear and exact understanding of the said embodiment. I do 20 not desire, however, to be understood as confining myself to the said specific construction and relative arrangement of parts inasmuch as in the future practice of the in-

vention various changes and modifications 25 may be made such as fall within the scope of my invention as defined in my appended claim.

Having described my invention, what I 30 claim and desire to secure by Letters Patent, is:—

A press comprising a frame having a bifurcation for the lateral introduction of a shaft bearing an element from which it is to be disassociated, and also having means 35 to offer an abutment to said element, a screw bearing in said frame, and an anti-friction member for interposition between confronting ends of the shaft and screw, said member having central tapered protuberances at its 40 ends, and the frame including a bracket with a threaded aperture for the bearing of the screw, said bracket fixed to and extending laterally from the frame and adapted to be fixed to an appropriate support. 45

In testimony whereof, I affix my signature.

PERCIVAL J. OLDERSHAW.
